[57] CLAIM

The ornamental design for a key holder, as shown and described.

DESCRIPTION

FIG. 1 is a perspective view of a key holder showing my new design;

FIG. 2 is an elevational view showing one of the two identical sides;

FIG. 3 is an end elevational view taken from the left of FIG. 1;

FIG. 4 is an elevational view showing one of the two identical edges;

FIG. 5 is a perspective view of the FIG. 1 embodiment shown in exploded condition;

FIG. 6 is an end elevational view taken from the right of FIG. 1;

FIG. 7 is an elevational view showing one of the two identical sides showing a second embodiment of my new design of FIGS. 1-6;

FIG. 8 is an elevational view showing one of the two identical edges;

FIG. 9 is an end elevational view taken from the bottom of FIG. 7;

FIG. 10 is an end elevational view taken from the top of FIG. 7;

FIG. 11 is a perspective view of the FIG. 7 embodiment shown in exploded condition;

FIG. 12 is a perspective view showing a third embodiment of my new design of FIGS. 1-6;

FIG. 13 is a perspective view of the FIG. 12 embodiment shown in exploded condition;

FIG. 14 is a perspective view showing the opposite side of that shown in FIG. 13;

FIG. 15 is a side elevational view, the circular member being the same throughout in appearance;

FIG. 16 is an end elevational view taken from the left of FIG. 12; and

FIG. 17 is an end elevational view taken from the right of FIG. 12 thereof.

*FIG. 1**FIG. 2**FIG. 3**FIG. 4**FIG. 5**FIG. 6**FIG. 7**FIG. 8**FIG. 9**FIG. 10*FIG. 16

FIG. 15

FIG. 17
